Daniel L. Baxter

By Howard E. Barlow
Atty.

UNITED STATES PATENT OFFICE.

DANIEL L. BAXTER, OF PAWTUCKET, RHODE ISLAND.

PACKAGE-WRAPPER.

1,384,115.

Specification of Letters Patent. Patented July 12, 1921.

Application filed April 30, 1920. Serial No. 377,825.

To all whom it may concern:

Be it known that I, DANIEL L. BAXTER, a citizen of the United States, and resident of the city of Pawtucket, in the county of 5 Providence and State of Rhode Island, have invented certain new and useful Improvements in Package-Wrappers, of which the following is a specification.

This invention relates to an improved protecting package wrapper, and has for its object to provide such a wrapper which is very simple and practical in construction, inexpensive to manufacture requiring the minimum amount of stock, and one which is 10 readily applied and secured to a package by folding the parts about the package and tucking in the flaps.

A further object of the invention is to provide such a package wrapper whereby the 20 top flap may be sealed for shipping, while either of the end flaps or wings may be readily withdrawn to open the package for inspection if desired as is required when shipped by parcel post.

The nature and advantages of the invention will be better understood when the following detail description is taken in connection with the accompanying drawings, the invention residing in the combination and 30 arrangement of parts as claimed.

In the drawings forming part of this specification, like numerals of reference indicate similar parts in the several views and wherein:—

35 Figure 1 is a perspective view of my improved wrapper as applied to a package.

Fig. 2 is a view showing my improved wrapper as cut from a sheet of stock in substantially the form of the letter T.

40 Fig. 3 shows the wrapper as partially folded.

Fig. 4 is a central section of the wrapper when in folded position.

With reference to the drawings, the blank 45 from which my improved wrapper is formed is cut from the sheet into the shape illustrated in Fig. 2, substantially in the form of the letter T having a shank 10 and a head portion 11 with oppositely extending wings 50 12. This shank is grooved, partially cut or weakened on the lines 13, 14 and 15 while the head portion is partially cut, grooved

or weakened on the lines 16, 17 and 18, to facilitate folding on these lines.

In forming my improved wrapper into 55 box shape the head member is first bent up on the line 18 forming a front wall 19 for the box or wrapper; next the wing members are bent rearwardly on the lines 16 forming end walls 20 for the wrapper; next the flaps 60 12 of the wings are bent inwardly to extend toward each other forming a portion of the inner rear wall. The shank portion of the T is now bent upward on the line 13 forming a bottom 21 and a rear wall 22 for the wrapper, next the shank is bent forward on the line 14 thus forming a top portion 23. The flap 24 is now tucked down inside of the front wall 19, which securely binds the whole together.

70 In shipping by mail or parcel post the top flap 24 of my improved envelop or wrapper, may be sealed while either of the end flaps 12 may be readily withdrawn for the purpose of inspection by the postal authorities and as readily replaced again securely closing the package against any possibility of accidental opening and that without cement or other fastening.

75 My improved wrapper is extremely simple and practical in its construction, requiring the minimum amount of stock and the simplest form of cutting dies to produce it, and when the flaps are folded and inserted 80 between the package wall and the wrapper wall all of the parts are securely locked, providing a most practical wrapper for protecting the package within.

85 The foregoing description is directed solely toward the construction illustrated, but I 90 desire it to be understood that I reserve the privilege of resorting to all the mechanical changes to which the device is susceptible, the invention being defined and limited only by the terms of the appended claim.

95 I claim:

As a new article of manufacture a protecting wrapper of bendable sheet material comprising a front wall having marginal wings folded back to form end walls, their extremities extending a substantial distance toward each other across the back of the wrapper and bound between the rear wall of the wrapper and the package contained within 100

it, the lower edge of said front wall having an integral foldable member extending rearwardly forming the bottom, then upwardly forming the rear wall, then forwardly forming the top of the wrapper, the front edge of the top portion being provided with a flap having a depth substantially one-half the height of said front wall and adapted to

be tucked inside of said front wall to be bound between said wall and the package 10 within to securely lock the wrapper about the package, the extremity of said flap being formed without laterally-extending tabs.

In testimony whereof I affix my signature.

DANIEL L. BAXTER.
